Des. 184,739
Patented Mar. 31, 1959

184,739

TOOTHBRUSH AND TOOTHPASTE HOLDER

Eugene L. Kanter, Norfolk, Va.

Application December 12, 1958, Serial No. 53,751

Term of patent 14 years

(Cl. D4—3)

Fig. 1 is a top plan view of a toothbrush and toothpaste holder showing my new design;

Fig. 2 is a front elevational view;

Fig. 3 is a view in perspective taken from the right and front;

Fig. 4 is a rear elevational view.

I claim:
The ornamental design for a toothbrush and toothpaste holder, as shown.
